UNITED STATES PATENT OFFICE.

EMIL DEISTER, OF FORT WAYNE, INDIANA, ASSIGNOR TO DEISTER MACHINE COMPANY, OF FORT WAYNE, INDIANA, A CORPORATION OF INDIANA.

HEAD MOTION FOR CONCENTRATING TABLES.

Application filed August 13, 1918. Serial No. 249,663.

To all whom it may concern:

Be it known that I, EMIL DEISTER, residing at Fort Wayne, in the county of Allen and State of Indiana, a citizen of the United States, have invented or discovered certain new and useful Improvements in Head Motions for Concentrating Tables, of which improvement the following is a specification.

The invention described herein relates to certain improvements in head motion for concentrating tables and has for its object a construction in which motion is transmitted from a crank or eccentric through toggles to the table or other object to be vibrated, said toggle members being so arranged relative to the crank or eccentric that the thrust resulting from moving the toggle members into alinement and the push of the crank or eccentric will approximately coincide in direction. The invention is herein-after more fully described and claimed.

In the accompanying drawings forming a part of this specification, Fig. 1 is a top plan view of a head motion embodying the improvements claimed herein, the cover of the casing being removed; Fig. 2 is a sectional elevation, the plane of section being indicated by the line II—II, Fig. 1; Figs. 3, 4, and 5 are views showing the moving parts or elements in forward mid stroke, and back positions respectively; Fig. 6 is a sectional elevation of the casing, the plane of section being indicated by the line VI—VI, Fig. 1; Fig. 7 is a sectional detail view, the plane of section being indicated by the line VII—VII, Fig. 1; Figs. 8 and 9 are respectively transverse and longitudinal sectional views of the roller; Fig. 10 is an end elevation of the rocker arm; Fig. 11 is a plan view of the toggle arm and Fig. 12 is a side elevation of the toggle, and Fig. 13 is a diagrammatic view illustrating the operation of the head motion.

In the practice of the invention, the movable members or elements of the head motion are enclosed within a suitable casing 1 which is provided with a removable cover 2 in order that the parts may be protected from dust and dirt, and is also adapted to form a suitable receptacle for oil for lubricating the bearing portions of the movable members. Around the upper edge of the casing 1 is formed a seat for the cover, the

supporting element of the seat being formed by a flange 3 and below the flange is formed a second or inwardly projecting flange 4 which is adapted to operate as a baffle to prevent the splashing of the oil upwards onto the seat of the cover. The employment of this secondary baffle renders it unnecessary to provide a packed joint between the cover and the casing to prevent the escape of oil. The driving shaft 5 is mounted in suitable bearings 6 formed outside of the casing and having caps 7 adapted to be secured by suitable means on top of the bearings. Below each of the bearings 6 is formed a pocket 8 which is in communication with the interior of the casing and forms a receptacle for oil which can be carried up onto the shaft 5 by means of an endless chain 9, thereby insuring the constant lubrication of the bearings of the shafts. At a point within the casing, the shaft 5 is provided with an eccentric 10 on which is loosely mounted a roller which may be of any suitable construction, but is preferably constructed as shown in Figs. 3, 8 and 9 and consists of, as shown particularly in Figs. 8 and 9, an outer shell 11 and an inner shell 12. Between these shells are formed pockets 13 into which the oil will be splashed in the operation of the mechanism through openings 14 in the ends of the shell. As shown in Fig. 9, the outer surface of the inner shell 12 is inclined inwardly towards the median line of the roller and at the junction of these inclined surfaces the shell is perforated so as to admit oil between the eccentric and the shell 12. This construction ensures a suitable lubrication of the surfaces of the roller and the eccentric which are in contact. A toggle arm 15 has one end mounted upon a pin 16 which is eccentrically mounted in bearings 17 on the casing. This eccentric mounting of the pin affords means whereby the position of the toggle arm with reference to the roller may be adjusted as required to vary the movement of the table as hereinafter described. In order to facilitate the rotary adjustment of the pin 16, it is provided with an angular extension 18 at one end and set screws 19 are provided for holding the pin in adjusted positions. The toggle arm is provided, adjacent to its free end, with a

concave seat 20 along which the roller will roll back and forth on the rotation of the shaft 5. At a suitable point, one end of a toggle 21 is connected to the toggle arm 15, the end of the toggle being preferably split for the reception of a fin forming the back of the arm 15. The connection of the toggle with the toggle arm is formed by a pin 23 passing through the prongs of the toggle 10 and the fin. The opposite end of the toggle is adapted to bear and exert a thrust on the rocker arm 24. In order to facilitate the removal of either the toggle arm or the rocker arm without removing the shaft, it is preferred that the lower end of the toggle should be formed with an open seat 25 as shown in Figs. 2, 3, 4, 5, and 12, such seat being adapted to bear upon a pin 26 passing through the prongs 27 at the end of the 20 rocker arm as shown in Fig. 10. Such construction will permit of the removal of either the toggle or the rocker arm by a withdrawal of the pin 16 or the pin 27 on which the rocker arm is mounted and without any 25 disturbance of the shaft 5 and its roller. In order to guide the toggle into position on the pin 26, a rib 28 is formed on the casing or shell, the upper surface of this rib being inclined and of such a height that the toggle 30 in sliding down the same will be directed into position on the pin 26. The upper or post portion 29 of the rocker arm 24 is provided with suitable guides for a block having on one side a bearing 30 for the pin 31, the 35 ends of said pin forming journals for bearings on the ends of the yoke 32, adapted to be connected to the table or other object to be vibrated. It will be understood that, as a general practice in the art, the movement of the table in one direction is effected 40 by the moving elements as hereinafter described, while the movement of the table in the opposite direction is effected by a spring not shown, which may be connected to the 45 table or to the post or to any other moving part.

In Figs. 3, 4, and 5, moving elements, to wit: the shaft, eccentric, roller, toggle arm, toggle and rocker arm with its post, are 50 shown in forward, mid- and rearward positions, respectively. These terms refer to the position of the post 29 forming part of the rocker arm and the table connected thereto. In Fig. 3 the parts have been 55 pulled to forward position by the spring and the return movements of the mechanism and the table are about to begin by the operation of the eccentric on the shaft 5 which rotates in the direction of the arrow α in 60 Figs. 3, 4, and 5.

When the parts are in the position shown in Figs. 3, or in forward position, the axis of the shaft 5 and the axes of the pins 23 and 26, or bearing points of the toggle 21, 65 are out of alinement, the axis of the pin 23

being to the left of a line connecting the axes of the shaft 5 and pin 26. As the roller is moved towards the outer end of the toggle arm by the eccentric 10, the toggle arm will be turned on its pin 16, the pin 23 moving downward and to the right. By reason of this movement, the rocker arm will be turned on its pin 27 not only by the action of the roller on the toggle arm but also by reason of the straightening of the 70 toggle joint. In mid position as shown in Fig. 4, the three points of the toggle are approximately in line and the further movement of the rocker arm and post to rear position will be due to the action of the eccentric on the toggle arm. 75 80

In the operation of a concentrating table, it is desirable that its forward motion should be gradually accelerated, the reversal abrupt and the return movement gradually retarded. These desirable characteristics are fully carried out in the operation of the mechanism described herein. 85

As hereinbefore stated, the movement of the rocker arm and post from forward position, as shown in Fig. 3, towards the mid position, shown in Fig. 4, is due not only to the action of the eccentric forcing down the toggle arm, but also to the movement of the center point or pin 23 of the toggle 90 joint into alinement with other points of the joint, and hence the movement of the rocker arm or post and table will be very rapid from forward position. From mid position as shown in Fig. 4, the movement of the rocker arm will be due principally to the action of the eccentric and to a small degree to the movement of the center point or pin 23 of the toggle to the right out of alinement with the other points of the toggle 95 and hence such movement will be slower. From rear position the movement of the table and the parts of the mechanism will be due to the action of the spring but controlled by the eccentric and the movement 100 of the center point of the toggle joint which movements will be the reverse of those just described. The preliminary return movement will be due to the movement of the eccentric allowing the toggle arm to 105 rise until mid position and thereafter an accelerated movement will be permitted, due not only to the upward movement of the eccentric but also to the movement of the center point or pin 23 of the toggle out 110 of alinement with the other points of the joint. 115

It is characteristic of the improvement that the movement of the rocker arm is due not only to the straightening of the toggle joint but also to the action of the eccentric which action is in the same direction as regards the effect on the rocker arm as the straightening of the toggle. 125

The improvement described herein em- 130

bodies what is known as a toggle mechanism, as will be seen by the diagram shown in Fig. 13, the shaft 5 forming the abutment, the pin 26 the object to be moved, the part 21 one of the toggle bars, while the other toggle bar is formed by the arm 15 and the eccentric. It is the usual practice when straightening a toggle joint to apply power to the knuckle in the direction of the arrow 10 y. In the construction shown herein, the knuckle, i. e., the pin 23, is moved into alignment or approximate alignment with the other points, by moving the knuckle or pin 23 in the arc of a circle having the axis 15 of the pin 16 as its center. It is a further characteristic of the improvement that the toggle member formed by the arm 15 and the eccentric is in fact an extensible member, the length of such member being increased and decreased on the rotation of the shaft 5 by an amount double the eccentricity of the eccentric 10, as will be clearly seen by reference to Fig. 13.

In the construction shown in Patent No. 25 1,088,682, granted March 3, 1914, to W. F. Deister, motion is transmitted from the lever 5 to the bell crank lever by a wiping or sliding movement of the block 8 on the roller 9; in other words, the bearing of the block on the roller is very narrow, being theoretically a line, and practical operation has shown that flat spots are soon formed on the roller and the apex of the block is worn away. In the construction 30 shown and described herein motion is transmitted from arm 15 to the rocker arm 24 by a toggle member 21 provided at its ends with seats or bearings for the pins 23 and 26, said seats having widths substantially 35 equal to half the perimeter of the pins. Continuous use for many months has shown 40 there is no material wearing away of the surfaces of the pins and toggle member.

I claim herein as my invention:

45 1. In a head motion for concentrating tables the combination of an open topped case, a shaft having an eccentric portion on which is a loosely mounted roller, suitable bearings for the shaft on the case, a toggle 50 arm having one end pivotally supported within the shell and at one side of the shaft and having its other end curved to receive the roller on the eccentric, a rocker arm having a pivotal support on the opposite side of the shaft, said arms being so arranged that their free ends overlap below the eccentric portion of the shaft and a toggle having 55 pivotal bearings on the overlapping arms.

60 2. A mechanism for reciprocating concentrating tables, etc., having in combination a pivotally mounted member adapted to be connected to the table or other object, an eccentric, a toggle mechanism interposed between the eccentric and the pivoted mechanism, the several parts being so arranged 65 relative to one another that the knuckles of the toggle mechanism may move into and out of alignment with the axes of the eccentric and the point of bearing of the toggle on the 115

lative to one another that the knuckles of the toggle mechanism may move into and out of alignment with the axes of the eccentric and the point of bearing of the toggle on the pivoted member. 70

3. A head motion for imparting a reciprocating movement to concentrating tables, etc., having in combination an eccentric, two arms pivotally mounted on opposite sides of the eccentric, the free ends of the arms overlapping on one side of the eccentric, a toggle interposed between and having pivotal bearings on the arms, said members being so arranged that the pivotal points of the toggle will be caused to move into and out of 80 alignment with each other and the axis of the eccentric on the movement of one of the arms by the eccentric. 75

4. In a head motion for concentrating tables the combination of an open topped 85 case, a shaft having an eccentric portion on which is a loosely mounted roller, suitable bearings for the shaft on the case, a toggle arm having one end pivotally supported within the case and at one side of the shaft 90 and having its other end curved to receive the roller on the eccentric, a rocker arm having a pivotal support on the opposite side of the shaft, said arms being so arranged that their free ends overlap below 95 the eccentric portion of the shaft and a toggle having pivotal bearings on the overlapping arms. 100

5. A head motion for imparting a reciprocating movement to concentrating tables, etc., having in combination an eccentric, two arms pivotally mounted on opposite sides of the eccentric, the free ends of the arms overlapping and provided with pins projecting laterally from the arms, a toggle interposed 105 between the pins on the respective arms, and having bearings on said pins approximately equal to half the peripheries of the pins, said members being so arranged that the points of bearing of the toggle on the respective 110 pins will be caused to move into and out of alignment with each other and the axis of the eccentric on the movement of one of the arms by the eccentric. 115

6. A mechanism for reciprocating concentrating tables, etc., having in combination a pivotally mounted member adapted to be connected to the table or other object, an eccentric, a toggle mechanism interposed between the eccentric and the pivotal mechanism, the several parts being so arranged relative to one another that the knuckles of the toggle mechanism may move into and out of alignment with the axes of the eccentric and the point of bearing of the toggle on the 120 pivotal member, an open topped case or shell for the reception of said mechanism, the sides of the case extending to such a height that the bearings of the several devices will be below the upper edges of the case or shell 125 130

and a removable cover for the case or shell.

7. A mechanism for reciprocating concentrating tables, etc., having in combination a shaft, an eccentric mounted on the 5 shaft, arms pivotally mounted on opposite sides of the eccentric having their free ends overlapping, a toggle having pivotal bearings on the respective arms, an open topped case or shell enclosing said parts and having

bearings for said shaft, and a removable 10 cover for the case or shell.

In testimony whereof, I have hereunto set my hand.

EMIL DEISTER.
